Application September 16, 1940, Serial No. 357,047

8 Claims. (Cl. 258—6)

My invention relates to amusement devices, and has among its objects and advantages the provision of an improved mail catching and delivering device particularly adapted for incorporation in toy trains.

In the accompanying drawings:

Figure 1 is a side elevational view of a car embodying my invention;

Figure 2 is a fragmentary view of the car and a top plan view of the mail catching and delivering device in its normal position inside the car;

Figure 3 is a view similar to Figure 2 but illustrating the invention adjusted for picking up a mail bag;

Figure 4 is a view taken along the line 4—4 of Figure 2;

Figure 5 is a view taken along the line 5—5 of Figure 3;

Figure 6 is a view taken along the line 6—6 of Figure 2;

Figure 7 is a perspective view of a supporting bracket;

Figure 8 is a perspective view of a sliding bracket which moves the mail bag to positions inside and outside the car;

Figure 9 is a view taken along the line 9—9 of Figure 2;

Figure 10 is a perspective view of a latch element;

Figure 11 is a perspective view of the car door;

Figure 12 is a diagrammatic view of a portion of the track with provisions made for actuating an electrically operated mail catching and delivering device in contradistinction to the mechanically operated type;

Figure 13 is an elevational view of the mail bag support with certain parts broken away for the sake of clearness;

Figure 14 is a perspective view of one of the mail bag releasing devices carried by the support;

Figure 15 is a top plan view of the structure of Figure 13;

Figure 16 is a top plan view of a track device for imparting pivotal motion to the mail bag catching hook;

Figure 17 is a plan view of an electrically actuated mail catching and delivering device in contradistinction to the mechanical device illustrated in Figures 1 through 11 and 13 through 16;

Figure 18 is a view taken along the line 18—18 of Figure 17; and

Figure 19 is a fragmentary detail view of one of the switches in an open position.

In the embodiment selected to illustrate my invention, the car 10 of Fig. 1 may be conventional with respect to size and general contour in conformity with conventional toy train cars. One side of the car is provided with a door opening 11 normally closed by a sliding door 12, which door is provided with a knob 13 to facilitate manual opening thereof. A slot 14 communicates with the door opening 11 to provide accommodation for the knob 13 as the door is moved to a full open position for uncovering the opening 11.

Fig. 11 illustrates the door 12, which door is provided with an extension 15 which covers the slot 14 in the closed position of the door. To the inner face of the door 12 is riveted a strap 16 having a finger 17 for connection with one end of a tension spring 18 having its other end connected with a lug 19 welded to an inverted U-shaped trough or track 20 which slidably receives the upper edge margin of the door 12, see Figs. 4, 5, 6 and 9. Trough 20 is welded to two upright straps 21 and 22 having their lower ends welded to a plate 23 lying on the car floor 24 and fixedly secured thereto by two screws 25. Strap 21 lies in the plane of the door 12 and constitutes a bumper therefor when the door is snapped closed by the spring 18. Diagonal braces 26 and 27 are respectively welded to the straps 21 and 22 and the plate 23 for reinforcing the straps. The lower edge of the door 12 is slidably guided by a U-shaped trough or track 28 having its ends welded to the straps 21 and 22.

Upon the plate 23 is mounted an L-shaped bracket 29 having its flange 30 welded to the plate and its flange 31 positioned upright at right angles to the floor 24 and to the longitudinal axis of the car, with both flanges extending the full width of the floor 24. An inverted trough or track 32 is fashioned along the upper margin of the flange 31, see Figs. 6 and 7, for the reception of the upper marginal edge of a guide plate 33 riveted to a plate 34 having its lower marginal edge positioned between the flange 31 and the bight of a channel 35 welded to the flange 30. Trough or track 32 and the channel 35 hold the plate 33 snugly against the flange 31, but the plate is slidably guided for movement toward and away from the door 12. Plate 34 is provided with a flange 36 which rides on the upper flange of the channel 35, and the plate is provided with a flange 37 which lies in a horizontal plane.

To the flange 31 is welded a finger 38 for connection with one end of a tension spring 39 having its other end attached to a finger 40 bent out of the plane of the plate 33. Plates 33 and 34 and the flange 37 constitute a carriage 41, as best illustrated in Fig. 8, for the mail bag catcher, and the spring 39 normally holds the carriage in abutting engagement with the finger 38. Plates 33 and 34 are recessed at 42 for the reception of the finger 38 to permit the recessed ends of the plates to be positioned closely to the adjacent side wall of the car 10.

Upon the plate 23 is mounted an inverted U-shaped support 43 having flanges 44 riveted to the plate, see Figs. 6 and 9. A bell crank 45 is pivotally mounted at 46 on the support 43, and the arm 47 of the bell crank is provided with a slot 48 for the reception of a pin 49 fixedly secured to the flange 37 of the carriage 41. Movement is imparted to the carriage 41 through pivotal action of the bell crank 45. Movement of the bell crank 45 in a counter-clockwise direction when viewing Figs. 2 and 3 shifts the carriage 41 from its normal position of Fig. 2 to the bag catching position of Fig. 3, and the carriage is returned to its normal position through the influence of the spring 39. Projecting inwardly of the door 12 is a lug 50 arranged in the path of the arm 51 of the bell crank 45 so that the bell crank is pivoted in a counter-clockwise direction through movement of the door 12 to an open position.

The mail bag catcher 52 is pivotally connected at 53 with the plate 37, and the catcher lies on the upper face of the plate 37 and is provided with an arm 54 which is offset to extend horizontally across the trough or track 32 and underneath the bight 55 of the U-shaped support 43. Pivotal movement of the catcher 52 is consummated through the medium of a pin 56 fixed to the arm 54 and projecting between two spring elements 57 and 58 fixedly secured to the plate 31, best illustrated in Figs. 2 and 7. Springs 57 and 58 are sufficiently stiff to provide the necessary resistance for controlling the pivotal movement of the catcher 52 as the catcher is moved from either position of Figs. 2 and 3 to the other position illustrated therein.

Door opening 11 is sufficiently large to permit the catcher 52 to swing freely therethrough, and the catcher is moved from the position of Fig. 2 to that of Fig. 3 by merely grasping the knob 13 and shoving the door open as far as it will go. While the door is biased to a closed position by the spring 18 and the carriage to its normal position of Fig. 2 by the spring 39, the catcher 52 is latched in its catching position of Fig. 3 by a trip latch 59 and the door, after being moved until the shank 60 of the knob 13 reaches the limits of the slot 14, returns a short distance in the direction of its normal closing position and is restrained from further movement through engagement with the plate 33.

Trip latch 59 is pivotally connected at 61 underneath the plate 37, which plate is provided with a slot 62 curved concentrically about the axis of the pivot 61 for the reception of a pin 63 fixed to the trip latch 59. Trip latch 59 is urged gently in a clockwise direction through the medium of a spring wire 64 having one end fixedly connected at 65 with the plate 37. In Figs. 2 and 3, the catcher 52 is provided with a recess 66 located to provide a hook 67. The wall 68 of the recess is curved to provide a wide mouth for entrance of the mail bag into the recess 66, and

the edge 69 of the recess is provided with a notch 70 for the reception of the pin 63 when the catcher is moved to its catching position of Fig. 3.

Fig. 2 illustrates the pin 63 as being located a considerable distance from the notch 70, and the notch includes a cam edge 71 which swings into engagement with the pin 63 as the catcher is being moved from the position of Fig. 2 to that of Fig. 3 for camming the pin 63 into the notch, which camming pivots the trip latch 59 in a clockwise direction from the position of Fig. 2 to that of Fig. 3. In Fig. 3, the trip latch 59 extends transversely of the recess 66 and in Fig. 2 the trip latch is positioned substantially at right angles to the axis of movement of the carriage 41. While the spring 64 urges the trip latch 59 in a clockwise direction, the cam edge 71 provides positive means for camming the pin 63 into the notch 70. Spring 64 also prevents accidental displacement or positioning of the trip latch beyond predetermined limits. Figs. 4 and 5 illustrate the hook 67 as being U-shaped in cross section when viewed from the end with the plate 37 aligning with the space 72 to be receivable therein in the closed position of the catcher, as in Fig. 2. Referring to Figs. 5 and 10, trip latch 59 has an offset 73 adapted to extend underneath the wall 74 of the hook 67. Accordingly, trip latch 59 completely spans the recess 66 and the offset 73 permits the trip latch to be made of sufficient length to extend underneath the lower face of the catcher 52 in all positions of the trip latch.

In operation, the catcher 52 is effectively latched in the position of Fig. 3 through positioning of the pin 63 in the notch 70. When so positioned, the spring 39 exerts a pull on the carriage 41 but the pin 63 latches the catcher 52 against pivotal movement about the axis of the pivot 53, and the pin 56 exerts pressure on the spring 58, but a wedge-like filler 75 lies adjacent the spring near its point of connection with the plate 31 so as to prevent flexing of the spring at this point. Thus the carriage 41 is restrained from inward movement. As the mail bag strikes the trip latch 59, the trip latch is pivoted in a counter-clockwise direction for moving the pin 63 out of the notch 70 which frees the catcher 52 to permit pivotal movement thereof. Spring 39 then pulls the carriage 41 inwardly and the pin 56 imparts pivotal motion to the catcher 52 as the pin advances along the springs 57 and 58. With the carriage 41 positioned in accordance with Fig. 2, the pin 56 has pivoted the catcher 52 to the position of Fig. 2 so that the mail bag will be latched in the hook 67. Plate 37 is recessed at 76, which recess coacts with the hook 67 to provide an opening for receiving the mail bag. Trip latch 59 will yield in a counter-clockwise direction through the pressure of the mail bag thereon so as to provide ample accommodation for the mail bag between the hook and the edge of the plate 37.

Since the hook 67 retains a holding connection with the mail bag when the carriage is positioned according to Fig. 2, movement of the carriage to the position of Fig. 3 will automatically position the mail bag exteriorly of the car where it is accessible for replacement on its supporting stand located along the track. Mere opening of the door 12 as far as it will go conditions the catcher equipment according to Fig. 3, at which time the catcher equipment is effectively latched in its mail catching position and automatically returns

to the position of Fig. 2 through mere engagement of the mail bag with the trip latch 59.

In Figs. 13 and 15, I illustrate a stand 77 for supporting the mail bag 78 having a neck 79 which engages the trip latch 59. Stand 77 includes arms 80 and 81 each provided with a split eye 82 for releasable connection with an eye 83 attached to the end of the mail bag. Fig. 14 illustrates one of the split eyes 82, which eye is in the nature of a spring wire bent to form a loop 84 and diverging ends 85 meeting at the point 86 to provide a closed loop so as to effectively retain the associated eye 83, which eye may be easily pressed into the loop 84 by forcing the eye between the diverging ends 85. The two split eyes 82 are identical in construction and function to provide a releasable mount for the mail bag 78 as it is engaged by the catcher 52.

Stand 77 is secured to a base plate 87 pivoted at 88 to a supporting structure 89, and the base plate 87 is provided with a handle 90 to facilitate rotation of the stand so that the mail bag 78 may be precisely positioned with respect to its spacing from the car to secure proper alignment with the catcher 52. Supporting structure 89 may extend underneath the track 91 and be secured to the rails thereof.

In Figs. 17, 18 and 19, I illustrate a different form of catcher mechanism, which form is electrically operated. Upon the car floor 92 is secured an inverted U-shaped support 93 having flanges 94 and 95 secured to the floor by screws 96, the flange 94 being bent to provide an upstanding plate 97. A carriage 98 provides a mount for a catcher 99, which is identical with the catcher 52, and includes a plate 100 lying adjacent the plate 97 and having its upper marginal edge slidably guided by a U-shaped track 101. The lower marginal edge of the plate 100 is slidably guided between the plate 97 and an angle 102 secured to the flange 94 by some of the screws 96. U-shaped upper and lower tracks 103 and 104, respectively, are provided for slidably guiding the door 105, and the tracks are welded to upright straps 106 which may be welded to the adjacent side of the car 107. Tracks 103 and 104 are identical with the tracks 20 and 28 of Fig. 5.

A tension spring 108 has one end connected with a lug 109 welded to the door 105 and its opposite end connected with a lug 110 welded to the track 103 for biasing the door 105 to a closed position, with the door aligning with the right-hand strap 106 of Fig. 18 to bump thereagainst when moved to a closed position. The door opening 111 corresponds to the door opening 11 of Fig. 1 with the exception that it is devoid of a slot 14.

To the inner face of the door 105 is riveted a strap 112 provided with a pin 113 extending loosely through a slot 114 in a bar 115 pivotally connected at 116 with a support 117 riveted to the floor 92. Closely adjacent the bar 115 is located a solenoid 118 fixedly attached to the floor 92 by a bracket 119 bolted to the floor. The core 120 of the solenoid is provided with an eye 121 for the reception of a pin 122 fixed to the bar 115. Eye 121 is so fashioned as to permit the necessary relative movement of the pin 122 as the lever is oscillated to either of its extreme dotted or full line positions of Fig. 18. Movement of the core 120 imparts sliding motion to the door 105. Energization of the solenoid causes a relative inward movement of the core 120 which moves the door 105 to its full open position of Fig. 18 against the tension of the spring 108. Deener-

gization of the solenoid permits the spring 108 to move the door to its closed position.

Carriage 98 includes a plate 123 to which the catcher 99 is pivoted, as at 124, and the catcher 99 includes an arm 125 provided with a pin 126 for coaction with spring members 127 and 128. Arm 125, pin 126 and the springs 127 and 128 respectively correspond to the arm 54, the pin 56 and the springs 57 and 58. Actuation of the carriage 98, particularly to the catching position of Fig. 17, is accomplished through the medium of a bell crank 129 pivotally connected at 130 with the support 93 and oscillated through the medium of a solenoid 131 having its core 132 pivotally connected with the arm 133 of the bell crank. Solenoid 131 is fixedly secured to the floor 92 by a bracket 134 bolted thereto. To the plate 123 is secured a pin 135 which extends loosely through a slot 136 in the arm 137 of the bell crank. Energization of the solenoid 131 imparts clockwise rotation to the bell crank 129, which moves the carriage 98 and the catcher 99 from their positions inside the car to the catcher position of Fig. 17. Carriage 98 is biased to its normal position inside the car by a tension spring 138 which has one end attached to the carriage and its other end attached to an arm 139 attached to the plate 97. Thus deenergization of the solenoid 131 permits the carriage 98 to be moved inside the car by the spring 138.

Adjacent the solenoid 118 is located a switch 140, which switch includes a conductor 141 having a contact 142 and a flexible conductor 143 provided with a contact 144 normally spaced from the contact 142. Conductors 141 and 143 are insulated apart and fixedly secured to the floor 92 by a supporting bracket 145 also insulated from the conductors. Fig. 17 illustrates the pin 122 as being of such length as to be engageable with the flexible conductor 143 to bring its contact 144 into electrical engagement with the contact 142 when the door 105 is moved to its full open position through the medium of the solenoid 118. A strip of insulating material 146 is secured to the conductor 143 and arranged to be engaged by the pin 122.

A lead-in wire 147 has one end connected with the conductor 141 and extends through an opening 148 in the floor 92 for connection with a sleeve 149 which supports a contact shoe 150, with the sleeve 149 secured to an insulating mount 151 supported on the car truck indicated generally at 152. Contact shoe 150 is spring pressed and slidably engages a fourth rail 153. A wire 154 is lugged to the wire 147 and leads to the solenoid 118, the latter being grounded at 155. One end of a wire 156 is connected with the conductor 143 and leads to the solenoid 131, the latter being grounded at 157.

Fig. 12 is a diagrammatical illustration of the track 91 showing the train controller transformer 158 and a catcher transformer 159. The primary winding 160 is connected with the line wires 161 and the secondary winding 162 is connected with a wire 163 connected with the outer or ground rail 164. A wire 165 is connected with the third rail 166 and with a wiper element 167 arranged for selective engagement with contacts 168. A wire 169 connects the wire 163 with the secondary winding 170 of the transformer 159, the primary winding 171 of which is connected with the line wires 172. Secondary winding 170 is also connected with a wire 173 electrically connected with the fourth rail 153 arranged to be electrically engaged by the contact shoe 150. Interposed in

the wire 173 is a manually actuated switch 174.

Fourth rail 153 is energized through closing of the switch 174. As the mail car passes over the fourth rail 153, the switch 174 is closed and current is delivered to the solenoid 118 through engagement of the contact shoe 150 with the fourth rail. The door 105 is then opened through movement of the core 120. Upon closing of the switch 140 through engagement of the contacts 142 and 144, current is delivered to the solenoid 131, the energization of which attracts the core 132 and shifts the carriage 98 to the position of Fig. 17, which locates the catcher 99 in the bag catching position of that figure. The switch 174 is held closed just sufficiently long to bring the catcher 99 to its mail bag pick-up position.

In Fig. 17, the catcher 99 is provided with a trip latch 175 which is identical with the trip latch 59, and a spring wire 176 is also provided for engagement with the pin 177. Wire 176 has one end fixedly connected at 178 with the plate 123. With the exception of the electrical actuation of the mechanism for manipulating the carriage 98, the catcher 99 functions in the same manner as the catcher 52.

In the manually set catcher form, the mail bag is manually removed from the catcher. In the electrically actuated form, the catcher is projected to a catching position with such speed as to cause the trip latch 175 to kick the mail bag in the catcher free so that it may drop clear thereof. Thus the catcher will be conditioned for picking up the second mail bag already placed in position on the stand. Thus it is preferable to employ two mail bags in connection with the electrically actuated form.

Having thus described certain embodiments of my invention in detail, it is, of course, understood that I do not desire to limit the scope thereof to the exact details set forth except insofar as those details may be defined in the appended claims.

I claim:

1. In a mail car, a mail bag catcher comprising a track, a carriage movable on said track, a mail bag catcher means pivotally mounted on said carriage, a guide, a pivot on said catcher means slidably and pivotally engaging said guide, said guide being angularly positioned with respect to said track to impart pivotal motion to said catcher means when the carriage is moved along said track to place the catcher means in a mail bag catching position in one position of said carriage and in a bag retaining position in the normal position of the carriage, said catcher means having a mail bag receiving recess and said carriage having a part arranged to close said recess when said carriage and the catcher means are in their normal positions, resilient means biasing said carriage to its normal position, and a trip latch pivotally connected with said carriage and acting on said catcher means and coacting with said guide to restrain the catcher means from pivotal movement when the latter is in a mail bag catching position and for latching the carriage against movement by said resilient means, said trip latch spanning said recess and pivoted to a catcher releasing position when engaged by a mail bag.

2. In a mail car, a mail bag catcher comprising a track, a carriage movable on said track, a mail bag catcher means pivotally mounted on said carriage, a guide, a pivot on said catcher means slidably and pivotally engaging said guide, said guide being angularly positioned with respect to said track to impart pivotal motion to

said catcher means when the carriage is moved along said track to place the catcher means in a mail bag catching position in one position of said carriage and in a bag retaining position in the normal position of the carriage, said catcher means having a mail bag receiving recess and said carriage having a part arranged to close said recess when said carriage and the catcher means are in their normal positions, resilient means biasing said carriage to its normal position, a trip latch pivotally connected with said carriage and acting on said catcher means and coacting with said guide to restrain the catcher means from pivotal movement when the latter is in a mail bag catching position and for latching the carriage against movement by said resilient means, said trip latch spanning said recess and pivoted to a catcher releasing position when engaged by a mail bag, said car having a door opening and a door for normally closing the opening, and an operating connection between said door and said carriage for moving the latter to place the catcher means in a bag catching position through opening of the door.

3. In a mail car, a mail bag catcher comprising a track, a carriage movable on said track, a mail bag catcher means pivotally mounted on said carriage, a guide, a pivot on said catcher means slidably and pivotally engaging said guide, said guide being angularly positioned with respect to said track to impart pivotal motion to said catcher means when the carriage is moved along said track to place the catcher means in a mail bag catching position in one position of said carriage and in a bag retaining position in the normal position of the carriage, said catcher means having a mail bag receiving recess and said carriage having a part arranged to close said recess when said carriage and the catcher means are in their normal positions, resilient means biasing said carriage to its normal position, a trip latch pivotally connected with said carriage and acting on said catcher means and coacting with said guide to restrain the catcher means from pivotal movement when the latter is in a mail bag catching position and for latching the carriage against movement by said resilient means, said trip latch spanning said recess and pivoted to a catcher releasing position when engaged by a mail bag, said car having a door opening and a door for normally closing the opening, and an operating connection between said door and said carriage for moving the latter to place the catcher means in a bag catching position through opening of the door, said carriage projecting partly through said opening when the catcher means is in a bag catching position, and resilient means biasing the door to its closed position, said door engaging said carriage to restrain closing of the door when the catcher means is in a bag catching position but being moved clear of the door when in its normal position to permit closing of the door.

4. In a mail car, a mail bag catcher comprising a track, a carriage movable on said track, a mail bag catcher means pivotally mounted on said carriage, a guide, a pivot on said catcher means slidably and pivotally engaging said guide, said guide being angularly positioned with respect to said track to impart pivotal motion to said catcher means when the carriage is moved along said track to place the catcher means in a mail bag catching position in one position of said carriage and in a bag retaining position in the normal position of the carriage, said catcher

means having a mail bag receiving recess and said carriage having a part arranged to close said recess when said carriage and the catcher means are in their normal positions, resilient means biasing said carriage to its normal position, a trip latch pivotally connected with said carriage and acting on said catcher means and coacting with said guide to restrain the catcher means from pivotal movement when the latter is in a mail bag catching position and for latching the carriage against movement by said resilient means, said trip latch spanning said recess and pivoted to a catcher releasing position when engaged by a mail bag, an electric circuit including a control switch, and electrically energized means connected in said circuit and adapted for energization by said circuit and operatively connected with said carriage for moving the latter against the tension of said resilient means to position the catcher means in its bag catching position.

5. In a mail car, a mail bag catcher comprising a track, a carriage movable on said track, a mail bag catcher means pivotally mounted on said carriage, a guide, a pivot on said catcher means slidably and pivotally engaging said guide, said guide being angularly positioned with respect to said track to impart pivotal motion to said catcher means when the carriage is moved along said track to place the catcher means in a mail bag catching position in one position of said carriage and in a bag retaining position in the normal position of the carriage, said catcher means having a mail bag receiving recess and said carriage having a part arranged to close said recess when said carriage and the catcher means are in their normal positions, resilient means biasing said carriage to its normal position, a trip latch pivotally connected with said carriage and acting on said catcher means and coacting with said guide to restrain the catcher means from pivotal movement when the latter is in a mail bag catching position and for latching the carriage against movement by said resilient means, said trip latch spanning said recess and pivoted to a catcher releasing position when engaged by a mail bag, an electric circuit including a control switch, electrically energized means connected in said circuit and adapted for energization by said circuit and operatively connected with said carriage for moving the latter against the tension of said resilient means to position the catcher means in its bag catching position, said car having a door and said catcher means passing through said door, and electrically energized means operatively associated with said circuit and operatively connected with said door to open the latter before said first-mentioned electrically energized means is energized.

6. In a mail car, a mail bag catcher comprising a track, a carriage movable on said track, a mail bag catcher means pivotally mounted on said carriage, a guide, a pivot on said catcher means slidably and pivotally engaging said guide, said guide being angularly positioned with respect to said track to impart pivotal motion to said catcher means when the carriage is moved along said track to place the catcher means in a mail bag catching position in one position of said carriage and in a bag retaining position in the normal position of the carriage, said catcher means having a mail bag receiving recess and said carriage having a part arranged to close said recess when said carriage and the catcher

means are in their normal positions, resilient means biasing said carriage to its normal position, a trip latch pivotally connected with said carriage and acting on said catcher means and coacting with said guide to restrain the catcher means from pivotal movement when the latter is in a mail bag catching position and for latching the carriage against movement by said resilient means, said trip latch spanning said recess and pivoted to a catcher releasing position when engaged by a mail bag, an electric circuit including a control switch, electrically energized means connected in said circuit and adapted for energization by said circuit and operatively connected with said carriage for moving the latter against the tension of said resilient means to position the catcher means in its bag catching position, said car having a door and said catcher means passing through said door, electrically energized means operatively associated with said circuit and operatively connected with said door to open the latter before said first-mentioned electrically energized means is energized, resilient means biasing said door to a closed position, said carriage projecting partly through said door opening in the bag catching position of said catcher means, and said door engaging said carriage to be restrained from closing until the carriage and the catcher means are moved inside the car.

7. In a mail car, a mail bag catcher comprising a track, a carriage movable on said track, a mail bag catcher means pivotally mounted on said carriage, a guide, a pivot on said catcher means slidably and pivotally engaging said guide, said guide being angularly positioned with respect to said track to impart pivotal motion to said catcher means when the carriage is moved along said track to place the catcher means in a mail bag catching position in one position of said carriage and in a bag retaining position in the normal position of the carriage, said catcher means having a mail bag receiving recess and said carriage having a part arranged to close said recess when said carriage and the catcher means are in their normal positions, resilient means biasing said carriage to its normal position, a trip latch pivotally connected with said carriage and acting on said catcher means and coacting with said guide to restrain the catcher means from pivotal movement when the latter is in a mail bag catching position and for latching the carriage against movement by said resilient means, said trip latch spanning said recess and pivoted to a catcher releasing position when engaged by a mail bag, said car having a sliding door and said carriage and catcher means moving partly through the door opening when said catcher means is moved to a bag catching position, an electric circuit, electrically energized means operatively connected with the door carried by said car and connected with said circuit for opening said door, electrically energized means carried by said car and operatively connected with said carriage for moving the latter against the tension of said resilient means, said last-mentioned electrically energized means being electrically connected with said circuit, and a switch between said circuit and said last-mentioned electrically energized means and actuated by said first-mentioned electrically energized means, said switch being closed after said door is moved to an open position.

8. In a mail car, a mail bag catcher comprising a track, a carriage movable on said track, a

mail bag catcher means pivotally mounted on said carriage, a guide, a pivot on said catcher means slidably and pivotally engaging said guide, said guide being angularly positioned with respect to said track to impart pivotal motion to said catcher means when the carriage is moved along said track to place the catcher means in a mail bag catching position in one position of said carriage and in a bag retaining position in the normal position of the carriage, said catcher means having a mail bag receiving recess and said carriage having a part arranged to close said recess when said carriage and the catcher means are in their normal positions, resilient means biasing said carriage to its normal position, a trip latch pivotally connected with said carriage and acting

on said catcher means and coacting with said guide to restrain the catcher means from pivotal movement when the latter is in a mail bag catching position and for latching the carriage against movement by said resilient means, said trip latch spanning said recess and pivoted to a catcher releasing position when engaged by a mail bag, said car having a door opening, a spring biased door normally closing said opening, a manual grip secured to said door to facilitate opening thereof against the tension of the spring, and an operating connection between the door and said carriage for moving the latter to position the catcher means in a bag catching position when said door is moved to an open position.

RICHARD J. KLINGEBIEL.
